UNITED STATES PATENT OFFICE

ELIZABETH A. LINDEN, OF SEATTLE, WASHINGTON

DESIGN FOR A NOVELTY DOLL TOY

Application filed January 13, 1932. Serial No. 42,469. Term of patent 3½ years.

To all whom it may concern:

Be it known that I, ELIZABETH A. LINDEN, a citizen of the United States, residing at Seattle, in the county of King and State of Washington, have invented a new, original, and ornamental Design for a Novelty Doll Toy, of which the following is a specification, reference being had to the accompanying drawing, forming part thereof.

The figure is a perspective view showing my new design which is sold as a single article of manufacture assembled as shown.

I claim:

The ornamental design for a novelty doll toy, as shown and described.

ELIZABETH A. LINDEN.
